Des. 203,563
Patented Jan. 25, 1966

203,563

SPLICER FOR PUNCHED TAPE OR THE LIKE

Paul E. Becking, Menlo Park, Calif., and Kurt Kulka,
Houston, Tex., assignor to Data Link Corporation, Los
Altos, Calif., a corporation of Delaware

Filed Aug. 21, 1964, Ser. No. 81,401

Term of patent 14 years

(Cl. D61—1)

FIGURE 1 is a top plan view of a splicer for punched tape or the like, showing our new design;

FIGURE 2 is a front elevational view thereof; and FIGURE 3 is a right side elevational view thereof. We claim:

The ornamental design for a splicer for punched tape or the like, substantially as shown.
